S. Thomas

ATTORNEY

UNITED STATES PATENT OFFICE.

CHARLES EDWARD RIEDEL, OF DETROIT, MICHIGAN.

AIR-THRUST PROPELLER FOR BOATS.

1,180,430.

Specification of Letters Patent. Patented Apr. 25, 1916.

Application filed April 29, 1915. Serial No. 24,789.

To all whom it may concern:

Be it known that I, CHARLES EDWARD RIEDEL, citizen of the United States, residing at Detroit, county of Wayne, State of Michigan, have invented a certain new and useful Improvement in Air-Thrust Propellers for Boats, and declare the following to be a full, clear, and exact description of the same, such as will enable others skilled in the art to which it pertains to make and use the same, reference being had to the accompanying drawings, which form a part of this specification.

My invention relates to an air thrust propeller for boats shown in the accompanying drawings and more particularly pointed out in the following specification and claims.

The so-called "air thrust" propeller for boats is being readily adopted in localities abounding in shallow streams or upon inland lakes having weeds apt to become entangled in the submerged propellers of small launches. It has been found, however, that the submerged rudders employed in connection with air thrust propellers are objectionable when passing through water overrun with weeds, or when landing at a bank in shallow water, in either case it being often necessary to remove the rudder.

The object of this invention, therefore, is to overcome these objections by dispensing entirely with a submerged or other rudder; by mounting the device on a horizontally swinging platform adapted to be operated manually and within a prescribed arc, whereby the propeller blades may be shifted to either right or left that the boat may be likewise directed, or to a neutral position or radius that the boat may be driven directly ahead.

Other advantages and improvements will hereafter appear.

In the drawings accompanying this specification:—Figure 1, is an elevation of the device attached to the stern of a boat looking toward the propeller blades. Fig. 2, is a side elevation of the device attached to a boat, a fragmentary portion of the latter, only, being shown. Fig. 3, is a plan view of the same. Fig. 4, is a horizontal sectional view of a detail, taken on line 4—4 of Fig. 2.

Referring now to the letters of reference placed upon the drawings:—A, denotes a suitable prime mover or motor, preferably an internal combustion engine.

B, is a platform horizontally adjustable,

upon which the engine rests and to which it is secured.

B', is a stub shaft, preferably integral with the platform, journaled in a tilting frame C, in turn pivoted at c, to a detachable clamping device D, adapted to be engaged to the stern of a boat.

F, is an arm secured to the stub shaft B', for manually swinging the platform B, to which the motor is secured.

f, f, are stops carried by the tilting frame to limit the swinging action of the arm F.

G, is a suitable bearing carried by the tilting frame to receive the thrust of the downwardly extending stub shaft B', projecting from the swinging platform.

H, denotes a plurality of holes in the side of the tilting frame C, to receive and co-act with a removable bolt H', carried by the clamping device D, whereby the tilting platform may be adjusted within a pre-determined degree and secured in its adjusted position against accidental release, should the angularity of the boat's stern to which it is clamped, make this course necessary. It being obvious that by tilting the platform the propeller may be adjusted to a substantially vertical position, producing greater efficiency in operation.

I indicates the engine propeller shaft, and I', are propeller blades carried by the shaft.

J, denotes an annular guard frame encircling the path of the propeller blades I'.

K, indicates a wire fabric secured to the annular frame to protect the occupants of the boat from injury through accidental contact with the revolving blades.

L, indicates the fuel tank, and L', the usual carbureter.

Having indicated the several parts by reference letters the construction and operation of the device will be readily understood. When it is desired to drive the boat straight ahead, the horizontally swinging platform, upon which the engine is mounted is manually adjusted by means of the arm F, so that the propeller shaft is in line with the keel of the boat, it being obvious that the propeller blades mounted on the shaft will then be in a position to drive the boat straight ahead. To steer the boat either to the right or left, it is only necessary to adjust the platform carrying the motor, so that the propeller blades will be shifted either to the right or left according to the direction that it may be desired to take. In

order that the device may not be turned to too great a degree and thus avoid any possibility of upsetting the boat, stops f , f , are provided to limit the adjustment of the 5 swinging arm F, for actuating the platform.

Having thus described my invention what I claim is:

1. In a device of the character described, a prime mover, a propeller shaft operated by the prime mover, an air propeller carried by the shaft, a clamping device adapted for engagement with the frame of a boat, a tilting frame pivoted to the clamping device, means for securing the tilting frame when adjusted, a swinging platform supported by the tilting frame upon which the prime mover is mounted, and means for manually adjusting the platform whereby the propeller may be swung to drive the boat ahead or to the right or left as may be required.
2. In a device of the character described,

a prime mover, a propeller shaft operated by the prime mover, an air propeller carried by the shaft, a clamping device adapted to 25 be engaged to the stern of a boat, a tilting frame pivoted to the clamping device, means for securing the tilting frame when adjusted, a swinging platform having a downwardly extending stub shaft journaled in 30 the tilting frame, a suitable thrust bearing for the shaft carried by the tilting frame, an arm secured to the stub shaft for manually swinging the platform, and a pair of spaced abutments carried by the tilting frame for 35 limiting the swinging action of the platform.

In testimony whereof, I sign this specification in the presence of two witnesses.

CHARLES EDWARD RIEDEL.
